UNITED STATES PATENT OFFICE.

CHARLES F. GREENWOOD AND FREDERICK GREENWOOD, OF NORFOLK,
VIRGINIA.

DESIGN FOR A SPOON.

SPECIFICATION forming part of Design No. 20,916, dated July 7, 1891.

Application filed June 8, 1891. Serial No. 395,574. Term of patent 3½ years.

To all whom it may concern:

Be it known that we, CHARLES F. GREENWOOD and FREDERICK GREENWOOD, both citizens of the United States, residing at Norfolk, 5 in the county of Norfolk and State of Virginia, have invented and produced a new and original Design for Spoon-Handles, of which the following is a specification.

Our design is illustrated in the accompanying drawing.

The handle A is of the usual form or shape, the end of the handle being enlarged. On the enlarged end of the handle is a representation of St. Paul's Church, Norfolk, Virginia. Under the representation of the church are the words "Saint Paul's Church." Around the edge of the enlarged portion C and surrounding the representation of the church is ornamental shell scroll-work a and scroll-work b. Arranged longitudinally on the shank or han-

dle of the spoon at c is the word "Norfolk." Above and below this word on the handle are leaf-scrolls c', and below the leaf-scroll c' is ornamental scroll-work c'.

The words "Saint Paul's Church" and "Norfolk" form no part of our design, which consists, essentially, in a handle for spoons having a shank ornamented with scrolls and leaf-scrolls and having an enlarged end carrying a representation of St. Paul's Church, 25 of Norfolk, Virginia, around which are arranged scrolls and leaf-scrolls.

We claim—

The design for spoon-handles herein shown and described.
